HOSIERY WITH STRAIN ABSORBING ZONE
REINFORCED AGAINST CURLINGRichard H. Scheer, New Holland, Pa., assignor to
Vanity Fair Silk Mills, Reading, Pa., a corpora-
tion of Pennsylvania

Application December 24, 1936, Serial No. 117,591

5 Claims. (Cl. 66—172)

This invention relates to hosiery of that type in which a circumferential zone of fine grade covered elastic yarn is integrally interposed in the knitting above the knee, having so free and extensive a stretch, longitudinally of the stocking, as to function as a strain absorber, relieving the parts of the stocking below said zone from excessive stresses, thus preventing laddering.

In order for the strain absorbing zone to be entirely effective, it must consist of a great many courses of the knit rubber yarn. For example, I have made stockings with adequate strain absorbing qualities having thirty-six covered elastic rubber courses in the strain absorbing zone and while the number of such courses is not critical, it is to be understood that a very few courses will be insufficient to produce the desired result.

The obvious manner of producing a strain absorbing zone is to knit a wide band of the fine gage covered rubber yarn in the stocking below the welt and above the knee. It has been found however, that merely knitting such a wide strain absorbing band or zone has not been practical from the commercial standpoint inasmuch as the band is given to curling concavely in a transverse direction lying in the form of a circumferential channel when the stocking is unworn, impairing its sales appearance.

Patent No. 1,929,006, granted October 3, 1933, to Howard B. Snader, covers a means for avoiding this objectionable curled appearance. In said patent, the strain absorber consists of a plurality of narrow fine gage covered elastic rubber yarn bands alternating with narrow bands of the basic fabric of the stocking. The aggregate number of rubber yarn courses represents the total number of courses in the strain absorbing zone and is commensurate with the exemplary number of courses noted above.

Since the strain absorbing zone formed as described in my aforementioned patent is spread over quite a wide portion of the stocking, this may be objectionable to some part of the purchasing public so that a great deal of consideration and experimentation has been devoted to the quest of finding other means effective for the prevention of curling of the rubber fabric in the strain absorbing zone.

The object of the present invention is to provide in a strain absorbing zone a wide band of covered elastic rubber yarn fortified against transverse curling by a circumferential rib extending through the median portion of the covered elastic rubber yarn zone and itself being of covered elastic rubber yarn, the elements of which are constituted as thickened transverse wales and preferably extending obliquely with respect to the rib so that in the act of stretching they swing to a substantially perpendicular position with respect to the direction of the courses,

thereby augmenting the longitudinal elongation of the fabric in the strain absorbing zone.

Other objects of the invention will appear as the following description of a preferred and practical embodiment thereof proceeds.

In the accompanying drawing throughout the several figures of which the same characters of reference have been employed to designate identical parts:

Figure 1 is a side elevation showing the upper portion of a stocking embodying the principle of the present invention;

Figure 2 is a diagrammatic view illustrating a typical stitch by means of which the reinforcing rib is formed in the midst of the elastic rubber zone;

Figure 3 is a view similar to that of Figure 1, but on a somewhat reduced scale illustrating the curling which is inherent in a wide band of fine gage covered elastic rubber yarn; and

Figure 4 illustrates the ridges or wales swung to a position perpendicular to the direction of the courses in the stretching of the stocking.

Referring now in detail to the several figures the numeral 1 represents the welt portion of a knit stocking, having the strain absorbing zone 2 below the welt and above the knee. The numeral 3 represents a portion of the stocking below the strain absorbing zone and above the knee. The stocking is of that type knit from fine gage yarns, is of delicate texture and susceptible to laddering or runners.

The invention contemplates a stocking which will be supported from the top of the welt so that there will normally be some longitudinal stress in the fabric. When the knee is bent, there will be an extraordinary strain on the stocking fabric particularly in the region of the bulge of the knee. It is the function of the strain absorbing zone 2 to stretch preferentially to the basic fabric of the stocking when such a strain occurs. The stocking fabric is quite elastic due to the looseness of the mesh in the knitting and it is essential that the fabric in the strain absorbing zone 2 be even more elastic in order that the stresses in the stocking fabric below the strain absorbing zone shall be transferred to the fabric in said zone.

The strain absorbing zone is therefore knit of fine gage covered rubber yarn, preferably of latex, the fine gage of the yarn together with the very stretchable nature of the latex making the rubber yarn much more freely stretchable than the basic stocking fabric. The strain absorbing zone is knit integrally with the adjacent portions of the stocking. As was suggested in the object of the invention, it requires more than a few courses of the rubber yarn to provide a sufficiently extensive strain absorbing zone to be adequate for

the intended purpose. Quite a wide band is therefore necessary as shown.

Due to its free stretchability, it is impossible to knit the fine gage covered rubber yarn without tensioning it. Even the drawing of the loops by the needles tensions the rubber yarn. It is an inherent characteristic of the wide rubber strain absorbing zone that due to the tensioning of the rubber it curls concavely in a transverse direction as shown at 4 in Figure 3. This curling is disastrous to the appearance of the stocking when unworn since it produces a circumferential channel which is unsightly.

The present invention provides a circumferential mid-rib 5, in the rubber elastic strain absorbing zone which stiffens it and thereby reduces the curl to such an extent that it is practically imperceptible. Incidentally the rib 5 as will appear increases the longitudinal extensibility of the strain absorbing zone. It will be understood that the rib 5 is not produced by the intercalation of courses of the basic fabric or any other type of yarn. It is integral and homogeneous with the fine gage covered rubber yarn zone in which it appears. The nature of this reinforcing rib 5 will be best understood from a consideration of Figure 2 in which all of the knitting shown is within the strain absorbing band and therefore composed of the fine gage covered elastic yarn. The upper and lower parts 6 and 7 represent undifferentiated knitting. The middle portion or mid-rib 5 is formed by a circumferential row of picot or lace stitches 3. By preference the transferred stitches 8 are advanced in each course, so that the line of picot or lace stitches will be oblique with respect to the direction of the courses. This is not essential however for if the rows of lace stitches extend longitudinally they will still constitute a mid-rib 40 which will resist the curling in the middle of the strain absorbing band.

The effect of transferring the loops in making the picot or lace stitches is to place two stitches 9 and 10 on every loop forming oblique bars 11 of double thickness and in parallel circumferential series as shown. These project, in relief in the same manner as wales and are sufficiently stiff to resist the tendency of the strain absorbing band to curl. At the same time, the mid-rib 5 being made of covered rubber elastic yarn of fine gage, is stretchable and forms an integral part of the strain absorbing zone. The value of having the bars 11 run obliquely around the middle of the strain absorbing zone is that when longitudinal stress is placed upon the stocking and the fabric of the strain absorbing zone is expanded in the direction longitudinally of the stocking, the said bars will freely swing from oblique position to a position in line with the wales of those portions of the fabric represented by the reference numerals 6 and 7 as shown at 12 in Figure 4 so that whatever decrease in elasticity of the bars 11 may be attributed to the doubling of the loops in said bars is off-set by the change in the position of the bars from oblique to longitudinal.

It is to be understood by those skilled in the art that the particular pattern of stitching shown in the drawing and described, is merely by way of example and not to be construed as limiting the scope of the invention which includes any

and all patterns capable of accomplishing the same purpose.

What I claim is:

1. Knit hosiery having an elastic strain absorbing zone integrally knit from fine gage covered elastic rubber yarn, of such width as to have an inherent tendency to objectionable curling, the elastic rubber fabric in said zone being formed with elongated thickened portions of less elasticity than the basic fabric of said zone, obliquely positioned with respect to the direction of stretch, stretching with the basic fabric, but at a less rate, so that said thickened portions move into alignment with the direction of stretch, thereby compensating by their effective length increase for the diminution in elasticity which they suffer as a result of their thickness.

2. Knit hosiery having an elastic strain absorbing zone integrally knit from fine gage covered rubber elastic yarn, of such width as to have an inherent tendency to objectionable curling, the elastic rubber fabric in said zone being formed with thickened portions resisting the tendency to curl comprising short bars extending transversely with respect to the width of said zone and arranged in a band spaced from the top and bottom edges of said zone extending circumferentially of said zone.

3. Knit hosiery having an elastic strain absorbing zone integrally knit from fine gage covered elastic rubber yarn, of such width as to have an inherent tendency to objectionable curling, the elastic rubber fabric in said zone being formed with thickened portions resisting the tendency to curl comprising short bars arranged transversely in a band of less width than said zone extending circumferentially of said zone, said bars being oblique with respect to the width dimension of said band and movable as a whole when said strain absorbing zone is stretched to a position in which they lie in the longitudinal direction of the hose, thereby compensating by their movement as a whole for such diminution in their elasticity as results from their relative thickness.

4. Knit hosiery having an elastic strain absorbing zone integrally knit under tension from fine gage covered elastic rubber yarn, of such width as to have an inherent tendency to objectionable curling due to relaxation of the tension under which it is knit, the elastic rubber fabric in said zone being formed with means for resisting the said tendency to curling, said means consisting of a circumferential series of transversely extending rows of conventional lace stitches, with intervening bars thickened throughout the presence of the loops transferred in the formation of said stitches.

5. Knit hosiery having an elastic strain absorbing zone integrally knit from fine gage covered elastic rubber yarn, of such width as to have an inherent tendency to objectionable curling, the elastic rubber fabric in said zone being formed with means for resisting the said tendency to curling, said means comprising a circumferential series of transversely extending oblique rows of lace stitches with intervening bars thickened by the presence of the loops transferred in the formation of said stitches.
